UNITED STATES PATENT OFFICE.

ALPHONSO S. HARRIS, OF CHELSEA, MASSACHUSETTS.

AUTOMATIC FIRE-EXTINGUISHER.

SPECIFICATION forming part of Letters Patent No. 269,930, dated January 2, 1883.

Application filed August 19, 1882. (No model.)

To all whom it may concern:

Be it known that I, ALPHONSO S. HARRIS, of Chelsea, in the county of Suffolk and State of Massachusetts, have invented a new and useful Improvement in Automatic Fire-Extinguishers, which invention is fully set forth in the following specification, reference being had to the accompanying drawings.

This invention relates to that class of fire-extinguishers which are arranged in fixed positions, and are held inoperative by a plug secured by solder which melts at the required temperature, thereby releasing the confined water and rendering the extinguisher operative; and the said invention will hereinafter be fully described, and specifically defined in the appended claims.

Figure 1 is a longitudinal section of an extinguisher embodying my invention and shown as closed. Fig. 2 is a transverse section taken on line xx , Fig. 1. Fig. 3 is a perspective view of both the elastic body and metallic facing of my improved packing. Fig. 4 is a perspective view of the extinguisher, shown as attached to the supply-pipe and as in operation.

In said views, a represents the supply-pipe, or a coupling thereof, which depends from the ceiling or beams of the apartment in which the extinguisher is arranged for use. A threaded sleeve, b , formed with an angular collar, c , for actuating it, is threaded to pipe a , and upon its lower portion is threaded, to move freely, the angular collar d , to which the concave deflector e is secured by the bars or short rods f , of which three are usually employed.

At the center of deflector e is formed a circular recess, having the circumferential wall g and bottom h . A short tube, i , depends from the latter, the lower portion whereof is cut through by a series of longitudinal slits, t . A stem, j , is arranged to slide freely in tube i , and at its upper end it is formed with a chambered head, having a plate, k , and a circumferential rim, l , which together constitute a cavity or chamber to receive the packing, which is composed of an elastic disk, m , faced with a thin metallic disk, n , which is secured to disk m by cement or other suitable means. The rim l is of such diameter that the lower extremity of the wall of sleeve b will only bear upon the packing which is seated inside of

said rim. When the extinguisher is to be closed, in order that it may be in readiness to act automatically, collar d is turned down to the lower part of sleeve b , when stem j is raised until packing n is in contact with the sleeve, when the hollow tapering plug v is inserted in tube i , as shown in Fig. 1, and is there secured by solder, (which will be melted when the temperature is raised to the determined point,) 60 after which collar d is turned upward to produce the requisite pressure of the sleeve upon the packing to produce a water-tight joint. When the heat rises to the point at which the solder melts, plug v is ejected by the force of 65 the water acting upon the packing, when stem j falls, and its head and the packing fill the central cavity in the deflector e , as shown in Fig. 4.

Upon the upper side of the deflector I arrange a series of short trough-like studs, which serve as distributors or dividers of the water as it passes outward over the deflector, there being preferably twice the number of said distributors z in the outer row as in the inner row, 75 (shown at z'), said inner ones being arranged on a radial line passing midway between the outer ones, and said inner ones being arranged with their inner trough-like face nearly vertical, in order that the jets distributed thereby 80 may strike the ceiling nearly over the extinguisher, while the outer ones are arranged at an angle about midway between that of the inner ones and the upper surface of deflector e , in order that the jets therefrom may strike 85 the ceiling midway between the point where the jets from the inner distributors and that from the deflector encounter it.

By facing the elastic packing-disk m with a thin incorrodible metallic face of about one 90 five hundredths of an inch in thickness all the advantages of a yielding packing are preserved, while the danger of the adhesion thereof to the valve-seat is avoided; and when the valve is released and falls into the cavity in 95 the deflector its facing n constitutes, together with the upper surface of the deflector, a continuous metallic face, on which the escaping water falls and moves, while if the elastic disk m were uncovered, so that the water directly 100 encountered the same, it would move with less facility thereon, as all soft, yielding, or fibrous

- materials offer much greater frictional resistance to moving water than does a metallic surface; and by seating said packing in a recess surrounded by an inclosing wall, it cannot unduly yield at any point, and thereby cause leakage and consequent damage; and by forming plug *v* hollow or cup-like it presents a greater surface to the heated air, and hence the melting of the solder at the intended point in the rise of temperature is rendered more certain, and the inverted bottom of the cup furnishes the requisite bearing or seat for the valve-stem *j*; while by forming said plug tapering it can be held as securely by the solder, yet when once the solder is melted and the plug starts there is no danger of the solder being again set by the cooling action of the first-liberated water, as might be the case if the plug were of uniform diameter.
20. The slits *t* in tube *i* insure the uniform soldering of the meeting surfaces of the tube and plug *v*, and, besides, said slits serve to render certain the action of the heated air upon the solder. By forming a central recess in deflect-
25 or *e* the head of plunger *j* is allowed to fall therein, and insures a practically continuous surface to the deflector, whereby the water falling thereon moves in a smooth volume instead of being broken up by an uneven surface.
30. The office and utility of the distributors *z* and *z'*, I have already stated. By means of the open space between the deflector and the valve-seat at the lower end of sleeve *b* screw-collar *d* may at any time be turned slightly downward, in order to determine whether the water-ways are in perfect condition and whether there is any adhesion between the valve and packing, and whether the entire apparatus is in good working order; and this may be positively determined without removal of any of the parts or the escape of a material or troublesome quantity of water.
35. At the inner side of the base of the distributor I form an opening, *a'*, through deflector *e*, in order that a sufficient quantity of water may fall through the same upon the floor directly beneath the extinguisher, which otherwise might not be wet by the water falling from the ceiling after it had been delivered
40 there by the extinguisher.
45. I am aware that it is not new to face an elastic packing with a thin sheet of metal or foil merely to prevent adhesion or wear. Hence I do not broadly claim the same, my invention in that behalf consisting in so combining the metallic facing with the respective coacting parts that it performs the double service of preventing the adhesion of the packing when the extinguisher is inoperative, and of furnishing a
50 portion of the upper surface or face of the deflector when operative. Nor do I broadly claim a deflector connected with the water-

conduit *b* by small rods *f*, and so leaving the remaining space open, as the same is not new; but I am, I believe, the first to so connect the conduit and deflector and with their distance apart adjustable, and I am, I believe, the first to combine with a conduit and deflector when so arranged a valve whose stem is seated and supported in the deflector, and which closes the conduit, and may be opened and closed by means of the adjustability in the distance of the deflector from the conduit.

What I claim is—

1. In combination with deflector *e*, the distributors arranged thereon and formed with an inner trough-like face adapted to receive and deliver the water in solid jets, substantially as specified. 75
2. The combination, with sleeve *b* and deflector *e*, formed with a central recess, of stem *j*, carrying the packing, composed of an elastic body, *m*, and a thin metallic facing, *n*, whereby said packing serves to close said sleeve, and when released therefrom said metallic facing coacts with the deflector in the delivery of the water, substantially as specified. 80
3. In an automatic fire-extinguisher, the tube *i*, arranged to receive the securing-plug *v*, and having the longitudinal slits *t*, substantially as specified. 85
4. In an automatic fire-extinguisher, the combination, with deflector *e*, of two series or rows of distributors arranged not only to deliver jets of water within the line of delivery of the deflector, but one within the other, substantially as specified. 90
5. In an automatic fire-extinguisher, the combination, with stem *j* and its bead or packing-support, of the deflector *e*, formed with a central recess corresponding with and adapted to receive said bead and packing, substantially as specified. 95
6. In an automatic fire-extinguisher, the combination, with deflector *e*, of the adjustable supporting-collar *d*, sleeve *b*, and connecting-rods *f*, uniting said deflector and collar, whereby the space between the deflector and sleeve is unobstructed, except by said rods and the valve-stem *j*, substantially as specified. 100
7. In an automatic fire-extinguisher, the combination of deflector *e*, with its central tube, *i*, valve-stem *j*, with its bead and packing arranged in said tube and deflector, adjustable collar *d*, arranged on sleeve *b*, and the rods *f*, connecting said collar and deflector, substantially as specified. 105
8. The deflector *e*, provided with distributors, and having openings *a'* arranged at the base of the distributors, substantially as specified. 110
